UNITED STATES PATENT OFFICE.

MORRIS W. JACOBI, OF WEEHAWKEN HEIGHTS, NEW JERSEY.

BAKER'S OVEN.

1,098,729.

Specification of Letters Patent.

Patented June 2, 1914.

Application filed October 30, 1913. Serial No. 799,238.

To all whom it may concern:

Be it known that I, MORRIS W. JACOBI, a citizen of the United States, residing at Weehawken Heights, county of Hudson, and 5 State of New Jersey, have invented a new and useful Improvement in Bakers' Ovens, of which the following is a specification.

This invention relates to a baker's oven of the class which is provided with overhead 10 heating pipes within the baking chamber, and comprises more essentially novel and efficient means for supporting said pipes and sealing the sustaining walls around the pipes against the escape of heat and gases.

15 In the accompanying drawing: Figure 1 is a longitudinal section of a baker's oven embodying my invention; Fig. 2 an enlarged cross section on line 2—2, Fig. 1, and Fig. 3 a perspective view of the thimble.

20 The oven, the general construction of which does not enter into this invention, is provided within the top of the baking chamber 10, with a plurality of tubular upper heating pipes 11, which are arranged directly beneath the girders 12 that support 25 the crown 13, the drawing showing but one of said pipes. Pipe 11, is supported at its front end by an overhead front partition 14, that depends from the crown 13, some distance 30 back of the front oven wall 15, and here receives the heating gases from a transverse flue 16. At its rear end, pipe 11 is supported by a rear partition 17, arranged some distance in front of the rear oven wall 35 18 the pipe delivering the heating gases to flues 19, that carry the gases over crown 13.

In order to accommodate the ends of pipe 40 11, the partitions 14, 17 are correspondingly apertured, and into each aperture is tightly fitted a tubular concentric sleeve or thimble 20, of a size to snugly encompass the pipe, though permitting its free axial expansion or contraction. Thimble 20 is provided with an integral circumferentially extending 45 flange which is set back from both faces of the partition, and is embedded within the

masonry thereof. This flange has the dual function of constituting an anchoring means for the thimble, and also of constituting a baffle or shield, around the thimble, that prevents the escape of gases and steam from the baking chamber, through the body of the partitions, whenever they become defective. That is to say, should the brick structure of the partitions crack in course of time, owing 55 to the combined influences of heat and load pressure, the flange by sealing the partition for some distance around the pipe forms a shield that effectively checks the escape of the heat and gases through the cracks, 60

At the mouth of the baking chamber 10, there is provided a door frame having an upper rearwardly projecting plate 22, which extends beneath the front partition 14. In order to permit the front thimble to rest 65 squarely on this plate, a segment of its flange 21, is cut away at the bottom, so that the flange has the shape of a mutilated annulus with a straight base 23. Not only does this construction increase the bearing 70 edge of the thimble, but it likewise permits its axial center to be considerably lowered, to thus correspondingly lower pipe 11, which is of considerable importance in increasing the heating factor of the latter. 75

I claim:

A baker's oven having a brick work partition provided with a transverse aperture, a tubular thimble seated therein, a circumferential flange integral with the thimble and extending a distance into the brick work to constitute a continuous gas- and steam-tight shield embedded within the brick work and surrounding the thimble, and a tubular heating pipe snugly encompassed by the thimble 85 to form a gas- and air-tight clip-joint therebetween.

MORRIS W. JACOBI.
